DESIGN FOR A BOTTLE OR SIMILAR CONTAINER

Grace Chess Robinson, New York, N. Y.

Application March 10, 1939, Serial No. 83,496

Term of patent 14 years

To all whom it may concern:

Be it known that I, Grace Chess Robinson, a citizen of the United States, residing at the Borough of Manhattan, city of New York, county of New York, State of New York, have invented a new, original, and ornamental Design for a Bottle or Similar Container, of which the following is a specification, reference being had to the accompanying drawing, forming a part thereof.

Fig. 1 illustrates the bottle or similar container embodying the ornamental design as it would appear when looked at from directly above, this being a top plan view.

Fig. 2 is a side plan view showing the bottle or similar container embodying the ornamental design.

I claim:

The ornamental design for a bottle or similar container, as shown.

GRACE CHESS ROBINSON.
